HAIR CURLER

Lucy Lenzi, New York, N. Y.

Application April 9, 1956, Serial No. 40,962

Term of patent 14 years

(Cl. D86--10)

Fig. 1 is a perspective view of a hair curler showing my new design;

Figure 2 is a side elevational view thereof;

Figure 3 is a rear elevational view of the opposite side; and

Figure 4 is a top plan view with the actuating member in the closed position.

I claim:

The ornamental design for a hair curler, substantially as shown.
